(57) **CLAIM**

The ornamental design for electric solder, as shown and described.

DESCRIPTION

FIG. 1 is a perspective view of an electric solder showing my new design;

FIG. 2 is a front view thereof;

FIG. 3 is a rear view thereof;

FIG. 4 is a left view thereof, with the opposite side being a mirror image thereof;

FIG. 5 is a top view thereof; and,

FIG. 6 is a bottom view thereof.

The broken lines depict portions of the electric solder in which the design is embodied that are not considered part of the claimed design.
